UNITED STATES PATENT OFFICE.

EDWARD S. HUTTON, OF MUSKOGEE, OKLAHOMA.

ROTARY WELL DRILL.

Application filed May 25, 1925. Serial No. 32,691.

This invention is for the purpose of the rapid rotary drilling of wells, chiefly oil wells of relatively large diameter.

This is a rotary drill and the invention consists in the combination with a fish tail or other bit for piloting the drilling apparatus, of improved means which follows the fish tail bit for enlarging the bore of the hole made by the fish tail bit. This enlarging means, therefore, is in the nature of a reamer.

The reamer is such that after it has been introduced into the well pipe and passes the lower end thereof, it will expand and drill the hole larger below the pipe, like a reamer. In this construction the cutter holders are pivoted so as to hang down or depend, while being moved down through the well pipe, and a spring and cam or inclined surfaces act on the cutter holder to push it outward into the expanded position. The cutter holder is mounted in a vertical recess and is substantially vertically movable with shoulders which limit the downward movement thereof so that the construction is relatively simple and easy to make and mount and the cutter holders extend relatively far in their seats or recesses, which makes them strong, and they and said recesses are free from the central water passage in the drilling apparatus, so that the water would not interfere with the operation of the cutter holders.

The full nature of the invention will be understood from the accompanying drawings and the following description and claims:

In the drawings Fig. 1 is a central vertical section through the well drilling apparatus, the upper portion being broken away and the lower portion shown in side elevation, and with the central part of the fish tail bit broken away and one cutter holder shown in elevation. Fig. 2 is a similar view showing the drilling apparatus below the lower end of the well pipe in drilling condition but with the fish tail bit largely broken away and one cutter holder shown in elevation. Fig. 3 is a horizontal section of line 3-3 of Fig. 1. Fig. 4 is a vertical section on the broken dotted line 4-4 of Fig. 1. Fig. 5 is the perspective view of a cutter holder centrally broken away.

There is shown herein an oil well pipe 10 and within it there is a tubular drilling stem 11 which is rotated during the drilling operation. The lower end of the stem is

internally threaded to receive the upper end of the reamer or well drilling tool. This apparatus consists of a central body portion 12 having a central upwardly extending reduced portion 13 externally threaded to screw into the lower end of the stem 11. Immediately below said reduced portion 13 the body portion 12 is enlarged and externally threaded to receive a cap 14 which screws thereon. Below the said last mentioned threaded portion the body 12 is enlarged so as to provide annular and downwardly sloping shoulders 15. At said shoulders the diameter of said body 12 is almost the same as the internal diameter of the well tube, see Fig. 3. Below the shoulder portion said body 12 is reduced and at its lower end provided with an internally threaded bore 16 into which the upper end of the fish tail bit 17 screws and is secured as shown.

In diametrically opposite sides of the shouldered portion 15 of the body 12 there are vertical grooves or recesses 20 open at the top and bottom, and each side wall of said recesses 20 has a vertical rib 21 as seen in Fig. 3, the two ribs projecting toward each other so as to reduce the width of the outer portion or opening of the recesses 20 above a horizontal shoulder 22 in each wall as seen in Fig. 4. In other words the vertical recesses 20 are transversely enlarged above the shoulders 22 by the side walls being cut out somewhat so as to leave said ribs 21 and shoulders 22.

The cutter holders 30 have in their lower ends round rotatable beveled cutters 31. The upper portion of each cutter holder 30 is widened to form lateral shoulders 32, as seen in Figs. 3 and 4. The cutter holder is insertable in said recess from above and the widened portions 32 thereof fit in the widened portions of the upper part of said recess, so that the shoulders 32 on the cutter holders and the shoulders 22 in the walls of the recess prevent the downward escape of the cutter holders, and the ribs 21 in the walls of the recess co-operates with the shoulders 32 to prevent the outward escape of the cutter holder. The depth of the upper portion of the recess 20 is greater than the thickness of the upper portion of the cutter holder so that the lower end of the cutter holder can be moved outward further from the center of the device, as shown in Fig. 2, to expand the cutters for enlarging

or reaming the hole cut by the fish tail bit. When the cutter holder is in its cutting or inclined position, as seen in Fig. 2, the outer faces of the shoulders 32 thereof engage the 5 ribs 21. The side of the cutter holder is shown in Fig. 5 and shoulders 32 are beveled downward and inward. When the cutter holders are in their contracted position, as shown in Fig. 1, the inner surface thereof 10 is almost vertical, but when the cutter holders are expanded, as shown in Fig. 2, the inner surface is at quite an inclination or the angle to the body 12 of the device and then the forward faces of the shoulders 32 are 15 vertical and engage the vertical ribs 21, and thereby the cutter holders are held firmly in place.

The cutter holders 30 are connected with a ring 34 by a contractile spring 35. The 20 ring 34 has a seat 36 cut out for receiving the upper end of the spring and it is held therein by a pin 37. The upper end of each cutter holder has a vertical recess 39 for receiving the lower end of the spring 35 and it 25 is secured therewith by a pin 38. The ring 34 is held down on the shoulders 15 of the body 12 by the cap 14, and the lower surface of the ring 34 slants downwardly and inwardly, the reverse of the shoulders 15. 30 The upper end of each cutter holder 30 also has a bevel surface 39 curved somewhat vertically and almost parallel with the lower slanting surface of the ring 34.

With the foregoing construction, when the 35 cutters are collapsed in the well tube, as seen in Fig. 1 the springs 35 hold them upward with the beveled surfaces 39 of the cutter holders bearing against the inclined surface 34 and this action of the springs 35 40 tends to force outwardly the lower ends of the cutter holders, so that when the cutter holders pass down below the bottom of the well tube 10, they will be forced out as shown in Fig. 2, into their expanded or cutting 45 position, and so that they will engage the wall of the well drilled by the fish tail or in which the tube 10 extends, and when the tube is rotated will cut the wall of the well and enlarge the well.

50 It is thus seen that the cutter holders are strongly held in their mounting and are yet capable of assuming their contracted and expanded positions. They will withstand great strain and when the well drill is elevated in the tube, the cutter holders will automatically be moved by the lower end of the well tube into their substantially vertical contracted position shown in Fig. 1.

Also it is to be noted that the mounting 60 of the cutter holders is remote from the water passage 40 down through the center of the drill so that nothing can pass therefrom into the recesses in which the cutter holders are mounted and no dirt or mud pass from 65 the latter to the water passage and choke it.

However, the body 12 of the device is provided with small lateral water passages 41 opening into the lower parts of the recesses 20 for cooling the cutters. The ring 34 is held in true position with reference to the 70 recesses 20 by a pin 42, as shown in Fig. 4.

By "pivotally mounted" is meant herein that the upper end of the cutter holder is mounted so the lower end may move outward or from the position shown in Fig. 1 to that 75 shown in Fig. 2, or the reverse, the upper end thereof being held by means substantially in the nature of a pivot so as to allow such pivotal action of the cutter holder.

The invention claimed is:

1. Rotary well drilling apparatus having a rotary body portion adapted to be introduced through a well pipe and having the upper end thereof reduced and threaded and below said reduced portion having upwardly and inwardly inclined shoulders and oppositely located vertical recesses, a ring 80 surrounding the contracted portion and fitting down on said shoulders, a cutter holder loosely mounted in each recess and having the upper end beveled to engage the inclined surface of the ring, said ring and cutter holder having spring seats therein, a contractile spring mounted in said seats and secured at each end to the ring and cutter holder respectively, and a cutter mounted in the lower end of the cutter holder.

2. Rotary well drilling apparatus having a rotary body portion adapted to be introduced through a well pipe and having the 100 upper end thereof reduced and threaded and below said reduced portion having upwardly and inwardly inclined shoulders and oppositely located vertical recesses, a ring 105 surrounding the contracted portion and fitting down on said shoulders, a cutter holder loosely mounted in each recess and having the upper end beveled to engage the inclined surface of the ring, said ring and cutter holder having spring seats therein, a contractile spring mounted in said seats and 110 secured at each end to the ring and cutter holder respectively, a cutter mounted in the lower end of the cutter holder, and a screw cap on the upper reduced end of the body 115 portion for holding said ring in place.

3. Rotary well drilling apparatus having a rotary body portion adapted to be introduced through a well pipe and having diametrically opposite vertical recesses with the upper portion of each recess enlarged at its sides so as to leave shoulders at the lower part thereof and a pair of vertical ribs at the outer portion thereof, a cutter holder in each recess with the upper end thereof provided with lateral extensions for fitting in the enlarged upper end of the recess and providing shoulders for engaging the shoulders and ribs in the walls of the recess to prevent the escape of the cutter holder and 125 130

yet permit it to rock so that the lower end may move outwardly, a cutter on the lower end of the cutter holder, a contractile spring secured to the upper end of each cutter holder and also secured in said body portion tending to withdraw the cutter holder upward, the upper ends of the cutter holder and the adjacent wall of the body being bev-

eled so that they will cause the lower end of the cutter holder to move outward as the cutter holder is drawn upward, substantially as set forth. 10

In witness whereof, I have hereunto affixed my signature.

EDWARD S. HUTTON.
